RAZOR HANDLE

Roland L. Smith, Belmont, Mass.

Application July 23, 1935, Serial No. 32,315

1 Claim. (CL 30—85)

This invention is a razor handle for use especially in connection with safety razors, an object of which is to provide means whereby the handle may be flexed in order to more properly "set" the shaving edge to the face of the user.

A further object of the invention is to provide a flexible hand grip for the razor of such character that the degree of flexibility may be varied by the user without resorting to mechanical means for accomplishing this purpose.

A still further object of the invention is to provide a flexible handle for use in connection with safety razors which may be readily applied to razors now in use and which does not require any change in the form or construction of such razors.

A still further object of the invention is to provide a razor handle of the character and for the purposes mentioned which may be manufactured and marketed at low cost, which does not include any special or complex mechanism, which is applied to and removed from the razor in precisely the same manner as are handles now in use, and which will prove thoroughly practical and efficient in use.

With these objects in view together with others which will appear as the description proceeds, the invention consists in the novel construction, combination and arrangement of parts, all as will be described more fully hereinafter, illustrated in the drawing, and particularly pointed out in the claim.

In the drawing:

Figure 1 is a side elevation of a conventional or well known form of safety razor showing the application thereto of a handle embodying the invention.

Figure 2 is a similar view, with parts broken away to show the details of construction and mode of operation; and

Figure 3 is a perspective view of the handle head used in connection with the invention.

The invention consists generally in a flexible handle to take the place of the rigid metal handle now in use. The improved handle possesses characteristics which will permit of its being flexed readily in various directions. Associated with the handle is means which enables the user to vary the degree of flexibility by merely changing the position of his hand upon the handle. This feature is of importance, as it enables each user to obtain the flexibility suited to his particular requirement. The invention in the present instance is shown as associated with one particular type or make of safety razor, but it will

be understood that the inventive idea may be equally as effectively carried out in connection with other types of razors. It will be understood, therefore, that variations in the mechanical structure may be resorted to, to enable the device to be associated with other types or forms of razors.

Referring now more particularly to the drawing, 4 illustrates generally the blade holder part of the safety razor, which usually includes a centrally disposed and externally threaded stem or post 5, by which the holder, handle and blade are properly and securely held in assembled positions. This stem engages within an inferiorly threaded opening within the head 6.

The head 6 in the present instance is of the same type as is usually employed with razors of this character, except that it is provided with an axially disposed outwardly extending member or projection 7, over which is engaged and secured one end of the flexible handle 8. The projection 7 is of less diameter than the head 6 and provides a shoulder 9 substantially at the juncture of the head with the projection and with which the end of the flexible handle locks. The zone of the projection adjacent to the shoulder is of slightly less diameter than the medial portion of the projection, in order to cause a firm grip of the handle with the projection as will be hereinafter explained. The projection 7 tapers or decreases progressively in lateral dimension towards its outer end, as shown clearly in Figures 2 and 3.

The handle 8 is formed of closely coiled wire, forming in effect a coil spring whose various coils rest against each other. The transverse exterior diameter of the coil is substantially that of the head 6, and the coils at the inner end of the handle fit tightly over the projection 7. Due to the peculiar shape of the projection 7, the coil will in effect be "stretched" in binding engagement over the larger diameter of the projection and thus is locked securely to the head. The outer end of the spring has engaged therein the inner extremity of a closure or cap 10, the same providing a shoulder 11 against which the outer end of the spring locks.

The spring handle 8 normally assumes a straight position as shown in Figure 1, but may be readily flexed with the exertion of slight pressure in any desired direction and to practically any degree. By reason of the tapered projection 7 the degree of flexibility may be varied. By grasping the handle close to the projection, it is obvious that the resistance offered to the coils

by the underlying tapered projection 7 will be greater than when the handle is grasped more remote from the projection. By grasping the handle immediately over or adjacent to the projecting portion 1, little or no flexibility is afforded. The razor thus constructed automatically lends itself to the degree of flexibility desired, this degree being determined by the point of grasp of the handle.

10 The handle is applied to the razor by delivering thereto a rotary motion to cause the threads of the stem 5 to engage within the socket of head 6. The coils of the handle, therefore, will preferably be made left handed, so that clockwise 15 rotation to tighten the handle will cause the coils to bind and securely grip upon the projections 7 and 10 and thus obviate slippage.

A handle constructed in the form of a coil as described possesses a flexibility very desirable in 20 the shaving operation. This flexibility is not limited to angular directions but permits of the head rotating to limited degrees with respect to the handle. This action permits the blade to rest properly upon the surface and keeps the blade

tension at both ends uniform, notwithstanding undulations in the said surface.

From the foregoing, it is apparent that I have provided a safety razor handle of extremely simple and inexpensive construction, and which possesses such characteristics as will permit of that degree of flexibility desired by the user. It is obvious, however, that this function may be obtained by variation in the details without departing from the spirit of the invention.

10

What I claim is:

In a razor, a head, a projection integral with said head, said projection being circular in cross section and of a diameter less than the head at its juncture with the latter to form a shoulder, 15 said projection increasing slightly in diameter from said shoulder to substantially its medial point and then progressively decreasing in diameter to its extremity, and a coil handle enclosing said projection and of a diameter substantially 20 equal to the diameter of the projection at its juncture with the head.

ROLAND L. SMITH.
